HEATER UNIT

Paul D. Kilbury, Hawthorne, Calif.

Application November 4, 1950, Serial No. 194,066

8 Claims. (Cl. 219—39)

1

The present invention relates generally to heaters for fluid medium, and is more particularly concerned with self-contained heater units of the type which may be mounted in the space to be heated or in some remote location with ducts provided to transmit the air, and which distributes a heated fluid medium, such as air, by high velocity discharge from a blower or fan.

Heaters of this type are especially adapted for utilization in the heating of large spaces such as warehouses, stores, markets, homes, offices, sanitariums, and the like.

It is one object of the present invention to provide a heater of this type in which the heating is accomplished electrically, which is economical and efficient in operation; which is so constructed that large quantities of air will be subjected to the heating elements, and which may be quickly started and stopped as required with minimum heat losses.

A further object is to provide in devices of the herein described type, an improved heating chamber of novel construction, wherein the fluid medium to be heated is guided to the heating elements and apportioned in accordance with the distribution of heating surfaces of the heating element.

Another object of the present invention resides in the provision of novel means for applying a supplemental circulation of fluid medium, such as air, through the heating element so as to cool the heating element supports and efficiently utilize a greater amount of the heat generated by the heating elements.

Still another object is to provide a unique base structure for the heating unit, wherein the parts of the base are associated to provide a box in which the electrical connections may be carried to the heating elements, and in which the box may also be utilized as an inlet header for conducting a supplemental flow of air to the heating elements.

Further objects of the invention will be brought out in the following part of the specification, wherein detailed description is for the purpose of fully disclosing the invention without placing limitations thereon.

Referring to the accompanying drawings, which are for illustrative purposes only:

Fig. 1 is a prospective view of a heater unit embodying the features of the present invention;

Fig. 2 is an end view, partly in section, the section being taken substantially on line 2—2 of Fig. 1;

Fig. 3 is a horizontal sectional view through the heating chamber, taken substantially on line 3—3 of Fig. 2; and

2

Fig. 4 is a detailed sectional view showing the construction of one of the heating elements, taken substantially on line 4—4 of Fig. 3.

Referring now generally to the drawings, Fig. 5 illustrates a heater unit according to the present invention. The heater unit briefly comprises a base structure, as generally indicated by the numeral 10, which serves as a support for a blower 11 elevated above the base and having a driving connection with an electric motor 12.

The blower 11 has an outlet duct 13 extending from its periphery for directing a high velocity discharge of air from one side of the base structure. Inlet to the blower is through an axially connected duct 14 which is secured to the blower casing by means of a plurality of circumferentially spaced bolts 15 which permit angular adjustment of the outlet duct 13 to vary the direction of discharge from the blower as required for varied installations.

Provision is made for heating the inlet air to the blower, when necessary, a heater as generally indicated by the numeral 16 being mounted on the base structure on the opposite side of the blower from the driving motor 12. This heater is of substantially cylindrical construction and comprises a heating chamber 17 surrounded by an inner wall 18 which is formed by a plurality of spaced vertically extending baffles 19 which are spot welded or otherwise suitably secured at their lower ends to a ring member 20, and at their upper ends to a flared top wall member 21 which is connected at its apex with the inlet duct 14 by means of an elbow 22.

A plate 23 is supported upon the upper flanges of side rails 24 and 25 of the base structure, this plate forming the bottom of the heating chamber and extending outwardly beyond the inner wall 18 to form a support for an outer wall section 26 which is connected at its ends to a vertically extending plate member 27 by means of bolts 28. The outer wall section 26 and plate member 27 cooperate with the inner wall 18 to provide an annular inlet 29 for fluid medium at the upper end of the heater 16. Thus, the entering fluid will flow downwardly and into the heating chamber through the spaces between the baffles 19.

Referring to Figs. 3 and 4, it will be noted that the chamber 17 has mounted therein a plurality of tubular upstanding core members 30 of heat resistant material which serve as a support for a coiled heating element 31. The heating units so formed are mounted in circumferentially spaced relation in the chamber 17, each of the cores having a bottom mounting flange 32 which is secured to the bottom plate 23 by bolts 33.

which extend through the plate and through a terminal block 34 on the opposite side, the bolts being threadedly associated with nuts 35. The terminal block 34 is provided with passages 36 through which connector conductors are carried to the heating element, these conductors passing through an opening 37 in the plate 23.

As shown in Fig. 3, the opening 37 is of such diameter that it will extend beyond the side edges of the terminal block 34 so as to leave space for flow of supplemental air upwardly through the bore 38 of the core members 30 to cool the interior of the heating unit and collect heat from the interior of the core members. This air combines with the main air which is distributed by the blower 11.

It will be observed in Fig. 3 that the spacing between the baffles 19 is not uniform. This is due to the manner in which the heating surfaces of the heating elements are distributed. As shown, the spaces, as indicated by the numeral 39, radially opposite a heating unit are of less area than the spaces, indicated by the numeral 40, which admit air between adjacent heating units. With this arrangement, the efficiency of the heater is maintained at a high value and the inlet air is more uniformly heated than would be the case if all the baffles were uniformly spaced apart. This is an important feature of the present invention, the one which contributes to a large extent to its efficient and economical operation.

The base structure is of box-like construction, the side rails 24 and 25 being closed along their top flanges by the bottom plate 23 of the heater 16 and a horizontally disposed continuation 41 of the plate member 27. The bottom of the base structure is closed by a bottom plate 42, while the ends of the base structure are respectively closed by end wall members 43-43 which contain perforations or openings 44 therein.

The base structure just described forms in effect a junction box for the connections to the respective heating units within the heating chamber 17, supply and control circuits being carried to the interior box-like base structure through a conduit 45 which is connected by means of a conventional connector 46. The electrical wiring is thus protected and concealed in such manner that personnel cannot inadvertently make electrical contact with the conductors, thus providing a very desirable safety feature.

The perforations or openings 44 in the end wall members permit flow of supplemental air into the box-like structure which thus serves as a header for the air which is drawn through the respective heating elements.

From the foregoing description it is believed that it will be readily apparent that the heater unit provides a unique arrangement by which the indicated objects will be accomplished.

I claim:

1. In a forced air heater: a base structure having side rails associated with a top wall, a bottom wall and end walls to form a box-like assembly; means supported on the top wall and cooperating therewith to form a heating chamber for a fluid medium, said chamber having a top outlet for discharging heated fluid in an upward direction and a side inlet; a plurality of upstanding electrical heating units in said chamber in the flow path of fluid medium from said inlet, said heating units being mounted over openings in said top wall of the base structure and circumferentially spaced around the projected axis of

said top outlet; electrical connections to said heating units carried through the interior of the box-like base structure and said openings; and a supplemental flow path for fluid medium including openings in at least one end wall of said base structure, the openings in said top wall, and passages in said heating units.

2. A heater for a fluid medium, comprising: means defining a heating chamber for said fluid medium, said chamber having an outlet and an inlet; a plurality of upstanding electrical heating units in said chamber in circumferentially spaced relation; a plurality of circumferentially spaced baffle members outwardly disposed of said heating units in the flow path of fluid medium from said side inlet, larger spaces being provided between certain of said baffle members for admitting air between and into heat exchange relation with adjacent of said units, and smaller spaces between other of said baffle members for admitting air radially inwardly into heat exchange relation with each of said units; and means for conducting a separate flow of fluid medium through each of said heating units.

3. A heater for a fluid medium, comprising: means defining a heating chamber for said fluid medium, said chamber having a top outlet and a side inlet; a plurality of upstanding electrical heating units in said chamber in circumferentially spaced relation; and a plurality of circumferentially arranged baffle members outwardly disposed of said heating units having first separating spaces for radially admitting air between adjacent units for heating thereof, and second separating spaces for admitting air radially opposite each of said units, the first spaces being of a size to provide greater flow than the second spaces.

4. A heater for forced circulation of a fluid medium, comprising: means including a bottom wall defining a heating chamber for said fluid medium, said chamber having a top outlet for discharging heated fluid in an upward direction and a side inlet; a plurality of members of heat resistant material in said chamber having flow passages therein, said members being supported in upstanding position on said bottom wall in the path of flow of said medium from said inlet to said outlet, and having their flow passages circumferentially spaced around the projected axis of said outlet in communication with fluid medium inlet openings in said bottom wall; and electrically energizable heating elements carried by said members.

5. A heater for forced circulation of a fluid medium, comprising: a substantially cylindrical heating chamber having a bottom wall, a top wall containing an outlet for directing heated fluid in an upward direction and an inner side wall defining spaced flow openings for said medium positioned around the projected axis of said outlet; an outer side wall spaced from said inner side wall and cooperating therewith to define at its top an annular inlet opening for said medium; and heating means within said chamber in the flow path of said medium from said spaced flow openings.

6. In a heater unit having a power driven blower for circulating a heated fluid medium, a heater for the fluid medium, comprising: a heating chamber; an inlet duct and an outlet duct connecting with said chamber, said ducts being in concentric relation about a common axis; heaters in said chamber arranged about said axis; and baffles in the flow path of fluid from

the inlet duct to said chamber, for directing fluid flow past said heaters in a direction generally toward said axis.

7. A heater unit, comprising: a base; a blower having a directive outlet at one side only of said base, and an axial side inlet; means for driving said blower; an air heater supported adjacent one end of said base having an outlet connection with said blower inlet, and a horizontal annular air supply inlet surrounding said outlet connection; and means in said heater for heating said air during passage therethrough.

8. A forced air heating unit, comprising: a base structure; a blower housing supported on said structure having an air impeller therein rotatable about a horizontal axis; a side inlet duct to said housing admitting air at the axis of said impeller; an outlet duct from said housing for directing an outlet air stream from said impeller; external means on one side of said housing having a driving connection with said impeller; a

chamber on the opposite side of said housing having an inlet and an outlet in concentric relation with respect to a vertical axis, said outlet being connected with said side inlet duct; and air heater means in said chamber.
